UNITED STATES PATENT OFFICE.

THOMAS J. POWER, OF MILWAUKEE, WISCONSIN.

ADJUSTING AND LOCKING DEVICE.

Application filed November 14, 1924. Serial No. 749,957.

This invention relates to improvements in manually operable adjusting and locking devices. More particularly stated, this invention relates to means for the release and engagement of a manually operable worm with a gear such as is used to drive a drum in a dry tumbler or the like, whereby to adjust or lock such a drum.

It is the primary object of this invention 10 to provide a novel and improved mounting for a manually operable worm whereby such worm may be oscillated bodily to and from engagement with a worm gear, and may be positively locked, either in or out of such engagement.

It is a further object of this invention to provide a simple cam adjustment positively determinative of the position of a worm gear in a device of the character described.

15 In the drawings:

Figure 1 is a perspective view of a fragmentary portion of a dry tumbler provided with an adjusting and locking device embodying this invention.

20 Figure 2 is a plan view of the adjusting and locking device shown in Figure 1.

Figure 3 is a side elevation of the device shown in Figure 2.

Like parts are identified by like reference 25 characters throughout the several views.

It will be understood that the tumbler mechanism is illustrated for the primary purpose of exemplifying one construction in which my invention will be found useful. In 30 a dry tumbler the frame 10 carries a housing 11 having a door 12 through which the tumbler drum 14 is accessible. The tumbler drum is provided with one or more doors like that indicated at 15, which may be 35 brought into registry with the opening normally closed by door 12 of the housing, and may thereupon be opened to permit the introduction or removal of clothing from the drum.

40 It will be understood that the drum is mounted for rotation within the said housing and is connected with a gear 16 mounted externally of the housing. This gear is driven through any suitable mechanism for 45 the rotation of the drum. Such mechanism is not material to this invention, and consequently is not illustrated herein.

When the mechanism driving the cylinder 50 15 through gear 16 is brought to rest, and the door 12 is opened, the door 15 may or 55 may not be in registry with the opening of

door 12. It is necessary to have these doors in registry, if the door 15 is to be opened. Consequently, manually operable means is provided for the rotative adjustment of the 60 drum. Such means comprises the principal subject matter of this invention, and will now be described.

The sleeve 20 is mounted for oscillation upon the axis of a stud 21, which supports it from the housing 11 of the machine. Journaled in said sleeve, and confined against axial movement with respect thereto by means of collars 22 and 23, is a shaft 24, carrying a worm 25. The worm is adjustable 70 to and from positions of operative mesh with reference to gear 16 by the oscillation of sleeve 20 on the axis of stud 21. The two extreme positions of the worm 25 and shaft 24 are illustrated in full and dotted lines 75 respectively in Figure 3. Shaft 24 carries a hand wheel 26 by means of which it may be rotated manually to adjust the gear 16 when in mesh therewith. Thereby the drum 14 may be brought to a proper position in its 80 housing for the registry of door 15 with door 12.

It will also be obvious that as long as the worm 25 maintains its engagement with worm gear 16, the irreversible characteristic 85 of the worm will so operate as to lock the worm gear against rotation other than such rotation as may be brought about by the manual operation of the hand wheel 26. This is very important inasmuch as great 90 injury to the operator might result if the tumbler drum 14 were so mounted that it could change its position while the operator was engaged in introducing or removing clothing therefrom.

95 From the foregoing, it will be obvious that it is desirable to maintain the worm 25 positively in each of its two positions. If the worm could yield from its position of mesh with gear 16, then it could not serve as 100 a positive lock for such gear to maintain drum 14 against rotation. Likewise, if the worm could yield from its elevated position, out of mesh with said gear, it might accidentally drop into mesh with the gear 105 while the gear was in motion and cause serious damage to the driving mechanism.

For the purpose of ensuring the accurate and positive adjustment or oscillation of shaft 24 and worm 25, I provide a cam device including members 28, slotted at 29, in a direction angularly inclined with reference 110

to the axis of shaft 24. The members 28 are integrally connected to comprise a single fitting by means of the spanning elements 30, which are suitably apertured for sliding bearing upon shaft 24 and are extended at 31 and 32 in the form of laterally projecting arms. A shaft 33 which appears in dotted lines in Figure 2 is mounted in these arms and supports a sleeve 34 from which a handle 35 projects. The sleeve mounting for handle 35 permits the handle to be oscillated independently in a plane normal to shaft 24 while transmitting to the members 28 the axial movement of the handle.

15 A stud 37 projecting from the frame 10 of the machine is received within the inclined slots 29 of members 28 and supports at its outer end a latch plate 39 provided at 40 and 41 with notches into which the shank portion 42 of handle 35 is receivable.

It will be obvious that when the handle is oscillated to a horizontal position to be received into either of the notches, as indicated in Figure 3, the result will be to secure 25 the entire fitting, including members 28, against axial movement. The position of oscillatory adjustment of shaft 24 will thereby be fixed against the possibility of axial displacement and will be determined by the portion of the slot 29 in which stud 37 is disposed. If, for example, the handle 35 is engaged in notch 40 as shown in Figure 3, the stud 37 will be positioned in a portion of slot 29 which is relatively remote from shaft 24. Thereby the adjacent portions of the 30 shaft will be elevated a comparatively great distance above stud 37 to bring the worm 25 into operative mesh with worm wheel 16. This is the position into which the parts must be adjusted to permit of the manual 35 operation of the tumbler to a position in which the door 15 may be opened. Furthermore, when the parts are in a position for manual operation as aforesaid the worm and worm gear will be locked in mesh, and the irreversible characteristics of the worm will make it impossible for the machine to start.

In order to permit the starting of the machine it is necessary to lift handle 35 from 50 its position in notch 40 by oscillating it about shaft 33 in a counter-clockwise direction as viewed in Figure 1. When it clears the notch it may then be used to adjust the entire fitting including slotted members 28 to the dotted line position of the fitting. During such movement the inclined surfaces of slotted member 28 will act upon stud 37 to draw shaft 24 toward its dotted line position as indicated in Figure 3. Shaft 24, in 55 oscillating about the center of stud 21, will lift the worm out of mesh with worm wheel 16. Shaft 24 and worm 25 will be retained in this position of oscillatory adjustment by the engagement of the shank portion 42 of handle 35 with notch 41 into which the

handle will fall when released by the operator.

From the foregoing it will be apparent that I have provided means for engaging and disengaging the manually operable 70 worm 25 with worm wheel 16, such means being lockable in either of its two extreme positions to secure the parts in adjustment. It will be obvious, furthermore, that in locking the adjusting device to maintain the 75 worm in mesh with the worm wheel, I effect also the locking of the worm wheel itself whereby the operator of the machine is safeguarded in opening door 15.

I claim:

1. In a device of the character described, the combination with a worm gear, of a shaft oscillatorily adjustable on an axis substantially parallel to that of said gear, a worm connected with said shaft and adapted 80 in one position of oscillatory adjustment thereof to mesh with said gear; a fitting axially slidable with reference to said shaft and operatively connected therewith to transmit oscillatory adjustment thereto, and a relatively fixed member adapted for interaction with said fitting, said member and said fitting being provided with co-acting 85 surfaces, one of which is inclined with reference to the axis of said shaft, whereby the 90 axial adjustment of said fitting will be productive of shaft oscillation.

2. In a device of the character described, the combination with a pair of gears adapted for operative mesh, of a shaft carrying 100 one of said gears and oscillatorily for the adjustment of said gear to and from a position for said mesh, a fitting axially slidable with reference to said shaft and including an inclined surface, and a fixed member, said fitting being adapted to co-operate with said fixed member, whereby said surface will cause oscillation of said shaft.

3. In a device of the character described, the combination with a pair of gears adapted for operative mesh, of a shaft supporting 110 one of said gears and oscillatorily adjustable to move said gear to and from its position of mesh with the other gear, a handle operatively connected with said shaft for the oscillatorily adjustment thereof, and a relatively fixed part with which said handle is interlockingly engageable in a selected position of said shaft wherein said gears are in 115 mesh.

4. In a device of the character described, the combination with a shaft supported for rotative and for oscillatorily adjustment about a transverse axis, of a gear, a second gear carried by said shaft and adapted in one position of oscillatorily adjustment of said shaft to mesh with said first mentioned gear, a fitting connected with said shaft and provided with an inclined plane, and a second fitting adapted for interaction with said 125

plane, whereby to produce oscillation of said shaft about its transverse axis, one of said fittings being movable with respect to the other.

5. In a device of the character described, the combination with a shaft supported for rotative and for oscillatory adjustment about a transverse axis, of a gear, a second gear carried by said shaft and adapted in 10 one position of oscillatory adjustment of said shaft to mesh with said first mentioned gear, a fitting connected with said shaft and provided with an inclined plane, and a second fitting adapted for interaction with said 15 plane, whereby to produce oscillation of said shaft about its transverse axis, one of said fittings being movable with respect to the other and being provided with a handle engageable with the other of said fittings to 20 secure the movable fitting in adjustment.

6. In a device of the character described, the combination with a shaft and a worm carried thereby, of a bearing for said shaft oscillatory upon a transverse axis, a fitting 25 slidably connected with and axially adjustable relative to said shaft and provided with a cam groove inclined with reference to said shaft, a relatively fixed stud positioned to interact with said cam groove, a relatively 30 fixed latch plate having a notch, and a handle connected with said fitting for the adjustment thereof and oscillatory to and from a position for engagement with said notch.

7. In a device of the character described, 35 the combination with a worm gear, of a manually rotatable shaft supporting said worm,

a bearing for said shaft mounted for oscillation upon a transverse axis, a fitting slidably connected with said shaft and provided with laterally extending arms and with a cam 40 groove inclined with reference to said shaft, a stud operatively engaged in said cam groove, a relatively fixed locking plate, and a handle supported for oscillation between said arms and positively connected with said 45 fitting for the adjustment thereof axially of said shaft, said locking plate being notched to receive said handle, whereby to secure said fitting, said shaft and said worm in adjustment about the axis of oscillation of said 50 bearing.

8. In a device of the character described, the combination with a worm gear, of a manually rotatable shaft supporting said worm, a bearing for said shaft mounted for 55 oscillation upon a transverse axis, a fitting slidably connected with said shaft and provided with laterally extending arms and with a cam groove inclined with reference to said shaft, a stud operatively engaged in 60 said cam groove, a relatively fixed locking plate, and a handle supported for oscillation between said arms and positively connected with said fitting for the adjustment thereof axially of said shaft, said locking 65 plate being notched to receive said handle, whereby to secure said fitting, said shaft and said worm in adjustment about the axis of oscillation of said bearing, said locking plate being supported by said stud.
